UNITED STATES PATENT OFFICE.

JOSEPH KAUFMANN, OF NEW YORK, N. Y.

WATER-CLOSET CISTERNS.

SPECIFICATION forming part of Letters Patent No. 339,062, dated March 30, 1886.

Application filed October 14, 1885. Serial No. 179,827. (No model.)

To all whom it may concern:

Be it known that I, JOSEPH KAUFMANN, a citizen of the United States, and a resident of New York, in the county of New York and State 5 of New York, have invented certain new and useful Improvements in Water-Closet Cisterns, of which the following is a specification.

My invention relates to an improvement in water-closet cisterns, the object of the same being to provide a device of this character which shall be simple and economical in construction, durable and efficient in use, and so arranged as to prevent any stench or smell from passing through the cistern and permeating 15 the house; and with these ends in view my invention consists in certain novel features of construction, as will be hereinafter described, and pointed out in the claim.

In the accompanying drawings, Figure 1 20 represents a longitudinal sectional view of my improved cistern. Fig. 2 is a top plan view thereof.

A represents the outer casing of a water-closet cistern, constructed of any suitable material and of any suitable dimensions, and having the service-box B extending below the 25 same and cast integral therewith.

The service-box B is formed with a shoulder, a, on which is adapted to rest the service-box plate C, as shown in Fig. 1 of the drawings. The plate C is formed with a central opening, b, for the passage of the water from the cistern into the service-box, said opening having formed around it an upwardly-extending 30 flange, c, forming a valve-seat, as herein-after described. This plate is also provided with an opening for the admission of the cistern supply-pipe D, which latter is provided on its upper end with an ordinary 35 valve operated by a lever and float, (not shown,) said latter opening being provided with a downwardly-projecting flange or hub, d, encircling the supply-pipe D.

The bottom of the box B is provided with 40 an opening having a hub or flange, e, formed around it, also encircling the supply-pipe D, which is threaded to engage with a thread 45 formed in the hub or flange e. This pipe is also threaded above the plate C, for engagement with the lock-nut f. It will be readily understood that by turning the pipe D, which is threaded in the hub e, the plate C will be

drawn down tightly on its seat a, and held in position by means of the nut f, a washer, g, being inserted between the nut and plate for 55 the purpose of rendering the joint water-tight. A suitable packing—such, for instance, as red lead—is inserted between the edges of the plate C and shoulder a, for the purpose of preventing any water from passing between them 60 from the cistern A into the box B.

The plate C is provided with another opening, having formed around it the hub or flange h, provided with a female screw-thread, through which passes the overflow-pipe E, extending 65 from the upper portion of the cistern into the lower portion of the box B.

The box B has formed in the bottom an opening, around which is constructed an upwardly-extending flange, i, the upper edge of 70 which is somewhat higher than the lower end of the overflow-pipe E. From the opening in the bottom of the box leads a pipe, k, to the basin of the water-closet, adapted to carry the water from the cistern thereto and wash 75 the same.

On the top of the flange c, formed around the central opening in the plate C, rests the valve F, preferably made of lead, and having a spindle, l, passing down through the same, 80 the under side of said valve F having a washer secured thereto by means of a lock-nut, m, fitting on a sleeve, n, secured to the spindle, for the purpose of allowing it to rest snugly on its seat. The upper end of the spindle l is 85 attached to the lever in the closet, by means of which said valve is operated, the lower end of the spindle being passed down through an opening, o, formed at the junction of the arms p, extending across the lower portion of the 90 valve-opening b, said lower end of the spindle having a pin, r, passing through it, for the purpose of preventing the spindle from being pulled out at the opening o.

Having now described the construction of 95 my improvement, I will set forth its operation.

When the lever of the closet (not shown) is pulled up, the valve F is raised from its seat, allowing the water in the cistern A to flow down through the opening b into the box B, ^{11 C} the valve being guided in its vertical movements by means of the spindle l. The water flows down through the opening in the bottom of the box through the pipe k to the basin of

the closet, and continues so to flow until the lever is lowered, and the valve F allowed to rest on its seat e. After the valve F has resumed its position on its seat the flow of water 5 from the cistern will be checked, and the water in the box will flow down the pipe k until it reaches the level of the upper edge of the flange i, which, as before stated, is somewhat above the bottom of the box, thus allowing a 10 quantity of the water to remain in the latter. As the upper end of the flange i is higher than the lower end of the overflow-pipe E, the level of the water is also above the said lower end of the overflow-pipe, and therefore keeps it 15 constantly submerged. By these means the stench or smell arising from the closet-basin when in use is prevented from passing up through the pipe k into the box B, and up through the overflow-pipe, the water in the 20 box tightly sealing the lower end of the latter.

I would have it understood that I do not limit myself to the exact construction and arrangement of parts shown and described, but

hold myself at liberty to make such changes as fall within the spirit and scope of my invention. 25

Having fully described my invention, what I claim as new, and desire to secure by Letters Patent, is—

The cistern A, formed integral with the box 30 B, and constructed with the shoulder a, the plate C, constructed with the opening b and flanges c d h, the valve F, the outlet-pipe k, and overflow-pipe E and inlet-pipe D, the said box being formed with the hubs e and i, 35 the upper edge of the latter being higher than the lower end of said overflow, substantially as set forth.

Signed at Brooklyn, in the county of Kings and State of New York, this 12th day of October, A. D. 1885. 40

JOSEPH KAUFMANN.
